UNITED STATES PATENT OFFICE.

THEODOR ERAGARD, OF HAMBURG, GERMANY, ASSIGNOR TO MACAO-WALZENMUHLEN-GESELLSCHAFT MIT BESCHRANKTER HAFTUNG, OF HAMBURG, GERMANY.

APPARATUS FOR MILLING CHOCOLATE AND LIKE PLASTIC MATERIALS.

Application filed May 10, 1926, Serial No. 108,170, and in Germany December 5, 1925.

This invention relates to apparatus for milling chocolate or like plastic materials of the type constituted by a mill comprising a set of planetary rolls rotating around a central roll and also around their own axes, and aims at a construction such that the material to be treated will be subjected not only to a grinding operation but will be thoroughly worked up by reason that it is given the greatest possible freedom of movement in the apparatus.

In the simplest construction according to the invention all or certain of the planetary rolls, and also, if desired, the central roll, are formed with through openings or gaps so that the material to be treated can pass transversely of the longitudinal axes of such rolls. The invention includes a particular formation of such gaps. In a modification there are substituted for certain of the planetary rolls beaters constituted by sets of bars which rotate around the central roll and also around their own axes. These beaters are especially adapted to promote the working up and the rubbing of the particles on one another and on the parts of the apparatus contacted thereby requisite for the comminution of the material.

In the accompanying drawing Fig. 1 is a longitudinal section illustrating a preferred construction of apparatus according to the invention.

Fig. 2 is a diagrammatic cross section thereof.

Figs. 3 and 4 are cross sections illustrating a variant employing rolls of modified section.

Fig. 5 illustrates a modification of the beaters.

The principle of the invention will be best understood by reference to Fig. 3.

The figure shows a construction comprising, as usual, rolls 1 which are planetarily driven around a central roll 2 in such wise that they rotate around the central roll 2 and at the same time rotate around their own axes. As distinguished from prior constructions, however, the apparatus of the invention presents this difference that, for example, solid rolls alternate with rolls having diametral through-pasages or gaps 3 permitting the material to pass through the gapped rolls in the direction transverse thereto. Preferably, also the central roll 2 is provided with a through passage 4. The

through passages 3 and 4 increase the capacity of the apparatus and permit the movement of the material within the apparatus necessary for the comminution thereof, the remaining parts of the peripheral surfaces of the rolls acting as grinding and comminuting surfaces.

In order to increase the capacity of the apparatus the gapped rolls may be of the cross section shown in Fig. 4.

The preferred construction according to Figs. 1 and 2 comprises rolls the section of which is best seen in Fig. 2. The rolls rotate in the direction of the arrows. The leading faces 5 of the rolls resulting from the formation of through passages in those rolls which are shown cross-hatched in Fig. 2 are substantially radial to the surfaces of the rolls. In addition, as shown in Fig. 1, the equispaced edges 6 and 7 of the through passages lie on helical lines. The consequence is that the material not only moves transversely of the rolls but also receive a movement in the longitudinal direction thereof. Also in this embodiment beaters 8 are constituted by cranked bars 8 alternate with gapped rolls, said bars being mounted on shafts 9 which rotate around the central roll 2 and around their own axes, the ends of the bars being, if desired, disposed helically to promote the movement of the material in the direction of the longitudinal axes, the bars radiating in staggered position similar to a star from the shafts 9, Fig. 5.

The drive is effected as usual in grinding mills. The shaft 11 of the central roll 2 projecting from the casing 10 carries a belt pulley 12 and within the casing 10 carries at both ends spur wheels 13 which engage spur wheels 14 on the ends of the planetary rolls 1 or beaters. The spur wheels 14 mesh with internally toothed surfaces 15 on the wall of the casing 10. The material is introduced by way of a hopper 16 and is discharged through an outlet 18 adapted to be closed by a shutter 17. The shafts 9 carry discs 19 which engage bearing surfaces 20 and 21 of corresponding breadth on the central roll 2 and on the rolls 1.

If desired, the rolls as also the beaters may be coned, the longitudinal axes of the cones diverging from one another towards one end of the casing or being parallel to one another. As usual in grinding mills, the diameters of the co-operating rolls may dif-

fer slightly from the diameters of the gear wheels fixed thereto so as to permit slip at the points of contact.

The gears 13 and 14 and the internally toothed elements 15 are preferably broader than necessary for the transmission of movement, so that, as they also lie within the casting and come in contact with the material, they may contribute to an appreciable extent to the comminution of the material.

In the preferred construction according to Figs. 1 and 2 the rolls and beaters are so arranged that they impart opposed movements to the material by reason that the central roll and the helically disposed beaters impel the material in the same direction while the planetary rolls impel the material in the opposite direction so that the material is projected on to the gears and subjected to a thorough milling action.

I claim:

1. Apparatus for milling chocolate and like plastic materials comprising a central roll, planetary rolls mounted for rotation around said central roll and also around their own axes, said rolls co-acting directly with said central roll and with one another, certain of which planetary rolls are formed with passages opening peripherally of said rolls so that the material can pass transversely of the longitudinal axes thereof, said passages extending longitudinally of said rolls and having the walls thereof obliquely directed to move material entering said rolls, in a longitudinal direction.

2. Apparatus for milling chocolate and like plastic materials comprising a central roll, planetary rolls mounted for rotation around said central and also around their own axes, said rolls co-acting with said central roll and with one another, certain of which planetary rolls, and also the central roll, are formed with helical passages so that the material can pass transversely of the longitudinal axes thereof, said passages extending longitudinally of said rolls and having the helices thereof so disposed as to move material entering said rolls longitudinally in opposite direction in said planetary and central rolls respectively.

3. Apparatus according to claim 1, characterized in that walls of the passages

through the rolls extend substantially from end to end thereof and are helically disposed.

4. Apparatus according to claim 1 further characterized in that the leading faces of the through passages in the rolls are substantially radial to the axes of said rolls.

5. Apparatus for milling chocolate and like plastic materials comprising planetary rolls rotatable around a central roll and also around their own axes, certain of which planetary rolls are formed with through passages or gaps so that the material can pass transversely of the longitudinal axes thereof, and characterized in that the planetary rolls having the through passages alternate with beaters also rotatable both around a central roll and about their own axes.

6. Apparatus according to claim 5, and further characterized in that the actuation of the rotating beater shafts is derived from the externally driven central roll through the medium of planetary gears arranged within the closed casing of the apparatus the teeth of said gears being of such breadth that they effect an appreciable part of the milling action.

7. Apparatus according to claim 5, and further characterized in that the beater shafts carry discs which bear on surfaces of suitable width on the planetary rolls and on the central roll.

8. Apparatus according to claim 5, and further characterized in that the actuation of the rotating beater shafts is derived from the externally driven central roll through the medium of planetary gears arranged within the closed casing of the apparatus, the teeth of said gears being of such breadth that they effect an appreciable part of the milling action, and further characterized in that the diameters of the co-operating rolls differ slightly from the diameters of the relative gears fixed thereto so that there is slip at the points of contact.

9. Apparatus according to claim 5, further characterized in that the central roll, planetary rolls, and the beaters are of conical formation.

In testimony whereof I have signed my name to this specification.

THEODOR BRAGARD.
